UNITED STATES PATENT OFFICE.

JOSEPH E. CAMP, OF WASHINGTON, ILLINOIS.

JACK.

1,136,934.

Specification of Letters Patent. Patented Apr. 27, 1915.

Application filed March 1, 1911. Serial No. 611,694.

To all whom it may concern:

Be it known that I, JOSEPH E. CAMP, citizen of the United States, residing at Washington, in the county of Tazewell and State 5 of Illinois, have invented certain new and useful Improvements in Jacks; and I do hereby declare that the following is a full, clear, and exact description of the invention, which will enable others skilled in the art 10 to which it appertains to make and use the same.

This invention relates to a hydraulic wagon-jack pertaining particularly to a jack for raising and dumping wagons, and for 15 raising automobiles bodily for making repairs thereto.

An object of the invention is to provide a lifting member operated by means of hydraulic pressure through a reclining cylinder into which fluid is pumped.

Another object is to provide, in a device of this kind, a series of pivotally connected members or links including means whereby to lock them relatively all of which, however, will appear in the following specification aided by the accompanying drawings in which:—

Figure 1 is a plan of my jack. Fig. 2 is a side elevation of the same. Fig. 3 is a plan 30 of a part of a piston-rod and a cross-head showing links connected thereto. Fig. 4 is a view of a "saddle" to engage and raise the axle of a vehicle. Fig. 5 is an end elevation of the same. Fig. 6 is a detail showing the 35 pivotal connection between a link and a part carried by the saddle shown in Figs. 4 and 5. Fig. 7 shows portions of a pair of guides in perspective. Fig. 8 is a transverse section of one of the guides shown in Fig. 7, together with other parts including a gear 40 wheel and rack. Fig. 9 is a plan of portions of my jack showing duplicate "saddles." Fig. 10 is a side elevation of parts of the same. Fig. 11 shows portions 45 of a guide in perspective. Fig. 12 is a detail of a link connection. Fig. 13 is a transverse section of a guide and parts of the links shown in Fig. 12, and means to secure 50 them in rigid relation. Fig. 14 shows the top of the guide and one of the links in cross section. Fig. 15 is an elevation of a guide and a modified form of pivotally connected 55 links, and means to fix them relatively. Fig. 16 is a side elevation of the same showing the guide in part section, and Fig. 17 is a transverse section of the same.

In Figs. 1 and 2, A indicates a long narrow platform having a portion B extending transversely thereof near one end secured in rigid manner thereto by any good means. 60 Lying upon the platform at one end is a cylinder C substantially in the position shown; there being a piston-rod D having the usual piston-head indicated in dotted lines in Fig. 2 at E.

As shown in one of my patents, for instance, that issued to me upon the 12th day of January, 1909, No. 909,281 for a wagon-dump, I have shown a cylinder in a substantially upright position and this cylinder 70 in the present application lies flat upon the platform as already stated, and, as with the cylinder of said patent, that in the present case is adapted for holding a fluid, such as oil, which is pumped from one side of the 75 piston E to the other and this is done through a pipe system and a pump. The latter is indicated at F and consists of a cylinder stationed between the members composing the portion B of the platform. To 80 the piston-rod G of said pump is connected a pitman G' through which motion is transmitted by an eccentric H on a shaft J driven from any source of power in any one of the usual ways.

A pipe K is connected at one end into the rear end of the pump and its other end is connected into the outer end of the cylinder C where it will deliver fluid behind the piston E to move it forward. L is a pipe also connected at one end into the inner end of the pump and at its other end into the inner end of the said cylinder C so that fluid can be pumped from that end into the said outer end of the cylinder behind the said piston E. 90 In each said pipe is a check-valve K' and L' respectively to permit passage of the fluid only in the proper direction as will be understood. Mounted above the cylinder is a vessel M connected with the inner end of the cylinder by a pipe N and connected also with the pipe K by means of a pipe O controlled by a valve P through a rod Q operated by the attendant. The said vessel M is employed for holding oil displaced by the piston-rod D and through it the fluid passes 100 from one end of the cylinder to the other at certain times as will appear later.

The piston-rod D is provided with a cross-head R through which extends a shaft S 110 provided at each end with a gear T and mounted upon the upper surface of the plat-

form beneath each gear is a toothed rack U with which the said gears mesh. Mounted upon the platform also, are two guides or tracks V which terminate at one end adjacent to the cylinder, the other ends curving upward as clearly shown in Fig. 2; these curve ends being supported, for instance, upon blocks W, only one of which is seen in Fig. 2. On the opposite end of the platform from that having the cylinder is a third guide or track 2, its outer end being straight and its other end curved upward and terminating between the upturned guides V and resting also upon a block W, Fig. 2, all three of the guides being properly and firmly secured to the said blocks. Each of these said guides, or tracks, as shown in several of the figures of the drawing and particularly in 7, 8, 11 and 14, consists of two U-shaped members placed opposite one another substantially in the positions shown and spaced apart to leave an opening 3 between them, the upper ends as shown in Fig. 7 being fixed relatively by means for example of plates 4. As shown in Figs. 1, 2 and 8 overhanging brackets 5 are provided which are suitably secured to the upper guide sections and these said brackets are arched over the toothed rack L and secured to the side of the platform being thus arched in order to permit the gears T to pass beneath them while properly holding said upper sections firmly with reference to the lower ones, said lower ones being suitably secured to the platform. Both said guide sections are thus properly spaced apart so that the shaft S may move between them. The cross-head R has an extension 6 whose ends project between the upper and lower guide portions as indicated in Fig. 1, and said extremities are provided with rollers 7, see Fig. 3 which move inside the guides and to said extremities are attached the links of two chains 8, at each of whose pivot is a pair of rollers 7, said chain extending through the guides and terminating above the upturned ends of the same where they are attached to a "saddle" 9 consisting of a block having a recess 10 in its upper side to engage the axle of a vehicle; its lower side being provided with depending portions 11, for instance, carrying a shaft 12 from which hangers 13 depend to which the end links of the chains just mentioned are pivoted. A chain 14 corresponding to the chains 8 is carried in the guide 2 hereinbefore mentioned, and this chain is likewise attached to a central depending hanger 15 on the shaft 12 of the saddle 9 and which corresponds to the members 13, there being rollers 16 on this chain corresponding to the rollers 7. A peculiarity of the chains is that their links, as clearly shown in Figs. 4, 5 and 6, are each provided at each end, opposite the pivot pins, with extending lugs 8² as

shown in Fig. 5, which meet when the said links form a straight line, said lugs being thus provided so that said links can pivot upon one another only in one direction beyond a straight line. The links pivot upon one another as they pass up the curved end of the guides V, for instance, and upon passing beyond the end of the latter they would remain in an upright position one upon another by reason of the abutting lugs 8², if there were no outside forces to cause them to move on their pivots and collapse. Now, since the chain 14 is constructed in the same manner but is reversed in position, its extensions thereof being at the opposite side of a link, as will be seen by comparing Figs. 5 and 6, it will be at once understood that one set of links will support or brace the other set and the chains will thus arise as a straight rod. To make the use of these lugs 8² clear and also to show the operation of the jack, it is to be stated that as the cross-head R moves forward, due to the fluid pressure against the piston E, the gears T meanwhile guiding the head in its forward movement and preventing the piston rod from springing sidewise, the chains 8 are pushed along the guides V, gradually forcing them upward outside the upright portions of said guides. As this occurs, the chain 14 is lifted up through its guide 2 and as all three of the chains reach a vertical position, the oppositely placed extensions of their links prevent the "saddle" 9 from swinging laterally in either direction.

As shown in Fig. 1 in dotted lines the vehicle to be raised is driven lengthwise of the platform and the front wheels rest upon the part B, the axle being immediately over the said "saddle" 9 as shown in Fig. 2.

I have adapted the jack for raising automobiles bodily by engaging both axles and this is done by using duplicate "saddles" 9. The guides corresponding to V and 2 are indicated in said Fig. 2 by 17 and 18 respectively and the "saddles" are shown at 9'. In order to accommodate automobiles, most of which vary in distance between the axles, the platform is made in two parts indicated by A' and A² the ends of which are shown adjacent each other in Fig. 10. These are adjustable relatively by means, for instance, of bars 19 bolted to the adjacent ends of said parts, said bars being slotted as at 20, for example, to permit the portions of the platform to shift end-wise. Since this provision is made, means must also be provided for adjusting those parts which shift the chains within the guides and it may be said that in this figure instead of pushing the piston outward from the cylinder in the direction of the saddles, it is drawn in the opposite direction by reversing the direction of movement of the fluid pumped through the pipes and in thus ap-

plying the power a pull instead of a push upon the chains with which the piston-rod is connected, is the result. To the cross-head R' on the piston in this instance is secured a rod 21 which extends in the direction of the "saddles" 9' between the guides 17. Attached to said rod are two members 22, for example, forming a link, and lying at opposite sides of the guide 18. The opposite ends of these said members 22, are secured to a duplicate of rod 21 indicated at 23, which, in turn, is provided with two members 24, said members 22 being adjusted upon the part 23 through bolts 25 and apertures 26 in said part 23 so that the entire rod connection controlled by the piston can be adjusted in length as well as the parts of the platform. The members 22 and 24 are connected to the chains in the guides 18 and 22 in any suitable manner, as for instance, by means of bolts 27, one of said chains being shown in Fig. 9 by the numeral 28. By this means when the piston rod is being drawn within the cylinder, the chains within the guides 18 will be carried up through the latter, the chains in the guides 17 following in the same manner as does the chain 14 in the guide 2 described with reference to Fig. 2. I have shown in Figs. 12, 13 and 14 a modification of a link structure by which one of the guides, for instance, 2 in Fig. 2, and 17 in Fig. 9, might be eliminated; said links carrying means for locking them relatively rigid when arising in a vertical line out of the guide.

It will be noted in the figures referred to that the links indicated by *a* and *b* are pivoted substantially as before and have the meeting shoulders *d* which prevent them from moving upon one another beyond a straight line in one direction, but said links are free to move in their opposite direction and it is my object to hold the links firmly in alignment or when in the position shown in Fig. 13 and in order that this may be shown I mount upon one side of each link an arm *e* carrying a gear *f*, both being carried on a pin *g* extending through said link and provided at the opposite side of said link with a head as at *h*, there being a friction washer or spring *j* beneath said head to provide constant friction and normally the arm *e* occupies the position shown in Fig. 12. Near the upper end of the track and indicated at *k* in Fig. 13 is mounted a toothed rack *m* with which the gears *f* of the limbs engage as they pass upward. This engagement results in imparting substantially a one-half turn to the gear and the arm thus placing the latter in position shown in said Fig. 13 where it overlies part of both limbs there being a shoulder *m'* extending outward from the adjacent link against which the free end of the arm may abut. By

this means it will be seen that the chain upon passing outside of and above the guide will retain a practically rigid vertical position.

In Figs. 15, 16, and 17 is shown another manner of securing the links relatively. The guide in these figures is shown at *o* and the rollers which carry the chain, made up of the links indicated by *p*, are carried in the slot created between the two parts of said guide as shown in Fig. 16; the pivots of the links forming the axles for said rollers as before. As in the form described above, the links are provided with the meeting shoulders *q* corresponding to shoulders *d* of the other figures, while each link is provided opposite the pivot with a projecting tooth or lug *r*. An arm *s* is pivoted on the link by means of a pin *t* extending through the latter, and said arm is provided with a friction roller *u*. Upon one of the surfaces of the guide *o* is a cam-track *v* which may be cast with said guide or secured thereto; this said track being made up of two oppositely placed members spaced apart a distance substantially equal to the diameter of the roller *u*, and, as shown in Fig. 15, the upper end of the track terminates near the middle of the width of the link while the lower end terminates substantially outside the line of the links.

In the figure last named, it will be observed that as the chain moves upward with the arms *s* normally in the position shown in that figure, the rollers of said arms will enter the lower end of the track and in following the same will be moved inwardly to the dotted line position carrying the arm to the said dotted line position to place its free end upon the projecting tooth *r* of the link below it. This having been done the chain still moving upward out of the guide will be maintained in a rigid upright position. When the chain descends the rollers will enter between the track portions and follow it until, upon passing out at the lower end, the arms *s* will have been removed from the vicinity of the teeth or lugs *r* thus permitting the links to move on their pivots in passing around the curve of the track.

The operation of the jack is much the same as that of my issued patent referred to. The vehicle, whether it be a wagon to be dumped or an automobile to be raised entirely from the ground, is driven over the jack so as to bring the axle or axles, as the case may be, above the respective "saddles." The pump in changing the fluid from one end of the cylinder to the other moves the piston in a direction to cause the chains to raise the "saddles." The movement of the fluid upon being interrupted and held sustains the vehicle in the raised

position. To lower said vehicle the valve P is opened thus letting the fluid move in the opposite direction due to pressure caused by the weight of the wagon which latter 5 descends to the ground. With a reclining cylinder such as I use a vehicle can be readily driven over it and the power thereof can be applied directly to the chains either by pushing them or by a pull upon them, the 10 entire structure being quite simple yet effective.

Having thus described my invention, I claim:

- 15 1. In a jack, the combination of a support, a guide or track mounted thereon including an upright portion, a member slidable in said guide comprising a series of pivotally connected portions each including a lateral extension at each end and at one 20 side of the pivot points of said portion, a second guide or track also including an upright portion opposed in position to that of the first said guide, and spaced sidewise therefrom, a member slidable in said guide 25 and made up of a series of pivotally connected portions and each including a lateral extension at each end at one side of the pivot points of said portion, and a stirrup to

which one of the portions of each member is pivoted.

2. The combination in a jack, of a support, a guide comprising two spaced track portions reclining thereon and having an upturned end terminating in a substantially upright portion, a member slidable therein 35 comprising a series of pivotally connected portions, rollers carrying the portions, each of the latter having a face at each end forming an abutment, a second guide disposed opposite to the first and having an upturned part terminating in the vicinity of that of the first guide and spaced therefrom; a member slidable in the same and likewise composed of a series of pivotally related portions and each provided with 45 means for limiting the movement of said portions relatively in one direction, and a stirrup to which both said members are connected above the said upturned ends of the guides.

In testimony whereof I affix my signature, in presence of two witnesses.

JOSEPH E. CAMP.
